13 Claims. (Cl. 197—131)

1

The present invention relates to an attachment for all writing or imprinting machines that is particularly adapted to produce reverse or mirror script masters for use in the duplicating systems whereby a master sheet having the material to be reproduced typed thereon in copyable ink is brought into contact with a copy sheet, and sufficient moisture, to dissolve a small amount of the ink from the master sheet to thus produce a copy. Certain advantages of my invention are not limited to this type of operation, but my invention exhibits its greatest advantages in the making of master sheets for use in the duplicating operation just referred to.

It is the principal purpose of my invention to provide means whereby the master sheet can be passed through the writing or imprinting operation and given the necessary mirror script copy on the back in hectograph carbon without danger of any smudging of the hands and clothing of the operator or of the master sheet. The importance of this cleanliness from smudging will be readily apparent to those who understand how easy it is to get smudges from handling sheets of carbon. The smudges are very objectionable from the standpoint of the operator because it takes time for cleaning up after inserting the carbon. They are also very detrimental from the standpoint of copies because any smudge on the master sheet will be reproduced in the same manner as the mirror script will be reproduced. According to my invention I combine with the platen of the writing or imprinting machine a strip of carbon and means for mounting the carbon so that the operator's hand need not touch the carbon strip itself, either on the coated or uncoated side, at any time. Likewise, I so arrange the feeding of the master sheet itself with respect to the platen that the master sheet and carbon sheet interengage only at the point of contact by the type, and one can slide relative to the other without smudging the master sheet with the carbon.

It is a further purpose of my invention to provide a device of this character with means whereby the entire surface of the carbon strip can be utilized even though only a small portion of the master sheets brought in contact therewith have any matter typed thereon.

It is also a purpose of my invention to provide a novel means for maintaining the master sheets fed through the machine free of streaks or smudges from the carbon due to one of them being moved with respect to the other.

My invention contemplates also the provision of a novel arrangement of parts whereby used car-

2

bon may be stored during the operation of typing the masters and disposed of at intervals without any danger of soiling the hands or clothing of the operator.

5 The nature and advantages of my invention will appear more fully from the following description and the accompanying drawings wherein a preferred form of the invention is shown. It should be understood however that the drawings and description are illustrative only and should not be taken as limiting the invention except insofar as it is limited by the claims.

In the drawings:

15 Figure 1 is a view in side elevation of a writing machine embodying my invention;

Figure 2 is a fragmentary view partly in section illustrating more in detail part of the mechanism shown in Figure 1;

20 Figure 3 is a fragmentary sectional view taken substantially on the line 3—3 of Figure 4;

Figure 4 is a plan view illustrating one embodiment of the invention;

Figure 5 is a front view of the device;

Figure 6 is a sectional view taken on the line

25 6—6 of Figure 1;

Figure 7 is a sectional view taken on the line 7—7 of Figure 5;

30 Figure 8 is a fragmentary perspective view illustrating a part of the mechanism shown in the Figure 7;

Figure 9 is a fragmentary sectional view taken substantially on the line 9—9 of Figure 7;

35 Figure 10 is a sectional view similar to Figure 7 but illustrating a slightly modified form of the invention wherein the carbon strip is wound from one spindle to another; and

40 Figure 11 is a fragmentary end view of the form of the invention shown in Figure 10, showing the interconnecting drive mechanism from the take-off spindle to the take-up spindle for the carbon strip.

In the present invention means are provided whereby a master sheet or strip 10 is adapted to receive on one side thereof a type imprint, while 45 on the opposite side thereof a deposit of hectograph carbon from a supply strip 11 is made in the form of a reverse image of the typed message. In the making of master sheets of this type it is often the case that the area occupied by the material supplied is very small in comparison with the total area of the sheet. When such master sheets are made by using a carbon sheet for each master sheet the process is quite wasteful of the material and it necessitates the handling of a 50 large number of sheets coated with carbon which

tend to smudge quite easily. This is objectionable from the operator's standpoint, and the possibility of getting smudge spots on the masters making them unserviceable is also a handicap.

It has heretofore been proposed in many cases to utilize carbon in the form of continuous strips for the making of copies. Continuous strip forms have been made and are available for use at present wherein the transfer medium or carbon is combined directly with the form of record sheet. Such forms require the use of as much carbon as master sheet and it necessitates the separation of the carbon from the master. There are many so-called snap-out forms developed to attempt to cure the difficulty of handling the carbon and the record sheet. According to my invention the necessity for using so much carbon or transfer sheet material is eliminated. Likewise, the necessity for effecting the separation of the used carbon from the master sheet is eliminated. Furthermore, both of these savings in time and material are accomplished with an improvement in cleanliness and simplicity of handling of the carbon.

I provide an attachment which can be readily adapted to different kinds of writing or imprinting machines including typewriters, addressing machines, bookkeeping machines and tabulating machines of various makes. This attachment consists essentially of two brackets 12 and 13 that are constructed to be mounted upon fixed parts of the machine. In the kind of machine to which the brackets are attached as shown herein, there is a cross bar 14 mounted on two rearwardly extending lugs 15 and 16 of the machine frame. The brackets 12 and 13 have bifurcated end portions 17 and 18 that fit over the cross bar 14 just inside the lugs 15 and 16. The illustrated machine is a typewriter that has a rectangular cross bar 19 between its two side frames 20 and 21. The brackets 12 and 13 are provided with notched extensions 22 and 23 respectively so that the brackets may rest upon the cross bar 19.

The brackets 12 and 13 serve as the supporting means for two side frames 24 and 25. These side frames are extended forwardly over the platen roller 26 of the typewriter so that the mechanism carried by the side frames is positioned to cooperate with the platen roller and the operating mechanism of the typewriter or other machine to which the platen roller is attached. In the form of the invention shown in Figures 1 to 9 inclusive the side frames 24 and 25 are adapted to support the carbon strip 11 with one end of the strip wound about a spindle 27 and with the other end of it inserted in a removable disposal container 28. The path of the carbon strip from the spindle 27 to the disposal container 28 is shown best in Figure 7 of the drawings. The carbon strip extends downwardly around the platen roller 26, and then upwardly and beneath a spring pressed idler roller 29 into an elongated guide passage 30 which is made up of two spaced plates 31 and 32. The plate 31 is fixed to the side frames 24 and 25, but the plate 32 is removably mounted. The upper end of the plate 32 is hung upon two pins 33 and 34 (see Figure 9) by means of clips 35 and 36. Part-way down the guide 32 from the clips 35 and 36 the side frames 24 and 25 have lugs 37 and 38 struck inwardly so that the guide 32 can lie against the lugs. The guide is cut out as indicated at 39, 40, 41 and 42 to permit the lugs 37 and 38 and the pins 33 and 34 to pass through the guide when it is necessary to move the guide for any purpose.

At the upper end of the passage 30 the carbon sheet is directed over a bar 43 and a plate 44, both of which are mounted in the side frames 24 and 25. It will be noted that the plate 31 is bevelled at its ends and extends into engagement with the bar 43 and into close proximity to the roller 29, that the plates 31 and 32 are curved at 165 and 166 to provide a gradually curving entrance to the passage 30 and that the plate 32 has a curved lip 167 at its upper end directing the strip 11 toward the bar 43 and the plate 44. The bar 43 has a groove 45 therein and a cutter blade 46 is adapted to cooperate with this groove in cutting off the carbon strip when the disposal container 28 is to be emptied and there is still carbon being fed from the spindle 27. The cutter 46 is a rotary one being rotatably mounted on a frame 47 that slides lengthwise between the side frames 24 and 25 on a rectangular guide bar 48. A hand lever 49 projects upwardly from the frame 47 for moving the cutter into cooperative relation to the groove and lengthwise thereof to cut off the strip 11.

The receptacle 28 as shown best by Figures 5, 7 and 8 is mounted for ready removal so that the carbon wound therein can be easily disposed of by holding the receptacle 28 over a waste basket and emptying the receptacle. The means for removably mounting the receptacle 28 comprises grooves 28a in the opposite ends of the receptacle and inwardly projecting elongated posts 28b and 28c fixed upon the side frames 24 and 25. The receptacle 28 is so mounted that it can be removed without difficulty, merely by grasping it in the middle and lifting it upwardly and outwardly. Thus it is entirely unnecessary for the carbon to be engaged by the hand of the operator and the receptacle 28 can be washed or cleaned in any way desired.

The platen roller 26 does not feed the master sheet 10 like the ordinary platen roller feeds paper in a typewriter or similar machine. The side frames 24 and 25 carry suitable mechanism whereby the sheets 10 or a web of master sheet material can be advanced without becoming smeared by the carbon strip 11. An examination of Figure 7 will illustrate the path of the master sheet 10. The machine illustrated, to which the invention is applied, carries a guide plate 50 that is adapted to direct a sheet into engagement with the platen roller 26 in the ordinary use of the typewriter. The typewriter shown, and similar machines usually carry pressure rollers 51 and 52 which are adapted to press the sheets against the platen roller 26. These pressure rollers however, can be moved and held out of the way of the path of the sheets guided by the plate 50, in machines of this character, and in accordance with my invention they are not utilized to press the master sheet against the platen roller. The guide 50 in such machines is spaced sufficiently from the roller 26 to allow free movement of a sheet 10 without binding the sheet, when its forward edge is led upwardly to a sheet advancing means forming part of this invention, that is carried by the side frames 24 and 25.

The sheet advancing means above referred to comprises two spaced shafts 53 and 54. The shaft 54 is a drive shaft and is journaled in the side frames 24 and 25, there being reduced portions 55 and 56 at the opposite ends of the shaft 54 (see Figure 6). The shaft 53 also has its opposite ends reduced in size as shown at 57 and 58, and these reduced end portions are slidably mounted in slots 59 and 60 that are provided in

the side frames 24 and 25. The shaft 54 has two separate rollers 61 and 62 slidably but non-rotatably mounted thereon. Each of these rollers comprises a core portion 63 and a soft rubber rim portion 64. The core portion 63 has a flattened face 63a (see Figure 7) in the bore therethrough to ride on a flattened side 65 of the shaft 54 so as to insure rotation of the rollers 61 and 62 with the shaft. The shaft 54 is rotatable by means of a handwheel 66 at one end and at the other end it has a ratchet wheel 67 fixed thereon. The reduced end portion 55 of the shaft has a flattened surface 68, and the ratchet wheel 67 has a flat face in the bore thereof to engage the surface 68. A washer 69 and a nut 70 engaging the reduced threaded end 55' of the shaft 54 serves to secure the ratchet wheel 67 in place. The reduced portion 55 also mounts a pawl shield 71, the function of which will be described more fully hereinafter. A wear plate 72 is mounted between the shield 71 and the enlarged portion of the shaft 54. The shaft 53 has two smaller rollers 73 and 74 slidably and rotatably mounted thereon. These rollers 73 and 74 are coupled to the rollers 61 and 62 by means of combination paper guides and coupling members 75 and 76.

The members 75 and 76 have bifurcated end portions 77 and 78 that engage in corresponding annular grooves 79 and 80 provided in the rollers 73 and 74. The members 75 and 76 are pivoted upon reduced end portions of the hubs 63 and are held in place by rings 81 and 82 which fit over the reduced end portions of the hubs 63. The rings are held in place by two set screws 83 and 84. Said members 75 and 76 have guide flanges 85 and 86 at the lower ends thereof.

In order that a sheet may be released after it is once gripped between the rollers 61 and 62 and the rollers 73 and 74, the shaft 53 is movable in the slots 59 and 60 away from the shaft 54. Normally the shaft 53 is urged toward the shaft 54 by two lever arms 87 and 88. The lever arms 87 and 88 are mounted upon a cross bar 89 that extends between the side frames 24 and 25. They have upwardly extending portions 90 and 91 which are connected by springs 92 and 93 to posts 94 and 95 that are secured in the side frames 24 and 25. A yoke member 96 has depending legs the end portions of which, 97 and 98 engage the opposite side of the shaft 53 from the arms 87 and 88. Normally the yoke member 96 is held away from the shaft 53 by means of a spring 99 that extends from said yoke back to a post 100 that is mounted in the side frame 24. The yoke however, can be latched in position to push the shaft 53 away from the shaft 54 by a latch member 101 that is pivoted at 102 on a post carried by the side frame 24. The latch is urged downwardly by a spring 103 that is also secured to the post 100. The latch is provided with a shoulder at 104 to engage an edge of the yoke 96.

Upon reference to Figure 7, it will be evident that by the mechanism described master sheets 10 can be drawn about the platen roller by means of the rollers 61 and 62 in cooperation with the rollers 73 and 74 and that this movement is independent of the movement of the surface of the platen roller that ordinarily serves this purpose in a machine such as that to which the invention is applied. The advantages of having the master or record sheet moving means move the sheet independently of the surface of the platen roller will be brought out more fully hereinafter in connection with means whereby it is possible to prevent the carbon sheet from engaging a

record sheet at all or to enable the carbon sheet to engage a master sheet only at the point where typing is being done.

It is desirable to have the roller 29 yieldingly mounted so that it can be lifted away from the platen roller 26 for purposes of getting the carbon started into the channel 30. I, therefore, mount the roller 29 upon two lever arms 105 and 106 that are pivoted upon a cross bar 107 connecting the side frames 24 and 25, said arms being spaced from the side frames by means of the tubular bosses 160 and 161 and said bar 107 having reduced threaded ends 162 with which nuts 163 engage to secure the bar 107 in position. The lever arms 105 and 106 have rearward extensions 108 and 109 respectively and springs 110 and 111 are connected from the lever arms 108 and 109 to pins 112 and 113 (see Figure 5) that are mounted on the side frames 24 and 25. The springs 110 and 111 yieldingly urge the roller 29 into engagement with the platen roller 26 at all times. However, it is a simple matter to lift the roller 29, if it is desired to enable one to pass the entering edge of a carbon strip between it and the platen roller.

One of the difficulties in attachments of this character that have heretofore been proposed is the difficulty of avoiding smudging of the master sheet as it passes over the carbon sheet where one sheet is moved at a different rate than the other. My invention provides means whereby this may be avoided and a sheet, with or without additional copy sheets can be fed through the machine and protected from smudge by engagement with the carbon sheet at the will of the operator. In other words, the operator can utilize the carbon strip for making reverse mirror script legends on the back face of the sheet corresponding to the type shown on the front face thereof, or he can, if desired, entirely prevent the carbon strip from engaging the record sheet material being moved through the machine. This feature of the invention is highly important because in so many cases the machine to which this attachment is applied must also be used for ordinary correspondence. The attachment does not prevent the machine from being used for that purpose and it makes it possible to make both a record carbon and a duplicating carbon in mirror script at the same time that an original piece of correspondence is written. The means that enable me to accomplish these various results comprises the combination with the carbon strip handling means and the added record or master sheet feeding means of the platen roller and a separating shielding member 114.

The shielding member 114 is of flexible sheet material. Examples of material that can be used for this member are ordinary paper sheets, cloth sheets, vellum sheets and synthetic resin sheets. The material should be tough and capable of withstanding hard usage because at certain times it is being pounded by the typewriter keys and at all times it is being subjected to engagement by the paper sheets that are fed through the machine. The shield 114 is looped through a slot 115 that is provided in one edge of a channel shaped clip 116. The material of the shield 114 is folded over and either fastened by stapling or allowed to hang from the fold, depending upon whether or not fastening is necessary. It will be noted from Figures 6 and 7 of the drawings that the clip 116 is adapted to hook over the cross bar 107. The clip is so constructed that it has two positions on the bar 107. The two outwardly bowed por-

tions 117 and 118 nearest the edge that mounts the shield 114 provide one position while the base portion 119 of the clip provides the other position. These positions are sufficiently far apart that when the portions 117 and 118 are in engagement with the cross bar 107 the end of the shield 114 is below the point "X" where the type engages the sheet 10.

To illustrate the exact position I have shown a type carrying lever 120 substantially in impressing position in Figure 7. When the type strikes the sheet 10 as shown in Figure 7, the sheet will be engaged with the carbon and receive a reverse imprint on the back. However, if the clip 116 is shoved down so that the part 119 thereof engages the bar 107, it will allow the shield 114 to extend farther around the platen roller 26 into position to block engagement of the sheet with the carbon strip beneath the type. In such a case the back of the sheet will receive no imprint from the carbon strip 11. It is thus possible for me to use the carbon strip or not use the carbon strip as desired. It is also possible to make ordinary carbon copies of correspondence by inserting a record sheet, a transfer carbon and a second sheet between the guide 50 and the shield 114, and the second sheet may or not have the reverse or duplicating message applied thereto depending upon the position of the shield 114.

Mention heretofore has been made of the manner in which the paper feed rollers 61 and 62 are driven by means of the ratchet wheel 67. The platen roller 26 is normally driven by a ratchet and pawl arrangement that can be adjusted to give longer or shorter strokes. This known construction is utilized in connection with my invention to establish drive means for the shaft 54 to the ratchet wheel 67. The particular mechanism is shown best in Figures 1 to 5 inclusive. The typewriter is provided with the usual carriage lever 122. This lever is pivoted at 123 on the frame of the typewriter and has an arm 124 that is connected to a link 125 that is adapted to operate the shaft 54 through a mechanism to be presently described. Another link 126, also connected to the arm 124, is adapted to rotate the platen roller 26 in the particular machine illustrated. The link 126 connects to a pawl arm 127 that is pivoted on the platen roller shaft 128. This pawl lever carries a pawl 129 that is adapted to engage a ratchet wheel 130 fixed to the platen roller. The pawl is held away from the ratchet wheel 130 by means of a shield 131 that can be shifted by a hand lever 132 so as to expose more or less of the teeth of the ratchet wheel to the pawl during a complete stroke thereof as effected by the lever 122. This mechanism or its equivalent is common in typewriters.

The mechanism by which I operate the ratchet wheel 67 on the shaft 54 includes the link 125. This link extends rearwardly and is supported at its rear end by an arm 133 that is pivoted on the side frame 25 at 134. The arm 133 also carries a second link 135 which is pivoted on the same pin 136 that pivots the arm 133 to the link 125. The link 135 connects to a pawl lever 137 that is mounted on the reduced portion 55 of the shaft 54 between the ratchet wheel 67 and the side frame 25. A spring pressed pawl 138 is carried by an extended portion 139 of the lever 137. A spring 140 normally urges the pawl 138 toward the ratchet wheel 67. However, the shield 71 is positioned to prevent the pawl 138 from engaging the ratchet wheel except when it is desired to

have the engagement effected and the period of engagement is controlled by adjusting the shield 71. This adjustment is accomplished by providing on the frame 25 a series of notches 141, 5 and providing on the shield 71 a spring pressed plunger 142 for engagement in the notches 141, the position of which is adjusted by means of the lever 164. The ratchet wheel 67 has a spring pressed roller 143 (see Figures 1 and 6) engaging it. This roller is carried by a lever 144 that is pivoted on a screw stud 145 on the side frame 25. A spring 146 urges the lever in such a direction as to press the roller 143 against the teeth of the ratchet wheel.

In normal operation of the machine for making master copies for duplicating purposes the carbon strip 11 is moved entirely by the platen roller 26. The shield 131 is therefore, so set that for each actuation of the lever 122 the platen roller will be advanced only one step. This means that all of the available space on the carbon strip will be utilized. The shield 71 however, may be set for double or triple space with the shield 131 set as above stated so that for actuation of the lever 122 the master sheet will be advanced farther than the carbon strip. When it is desired to move the master sheet through a large distance, this is accomplished by the hand wheel 66 without any movement whatsoever of the carbon strip. The guiding of the master sheet by means of the members 75 and 76 and the guide 50 is such that it is possible to reverse the movement of the paper by operation of the hand wheel 66 because there is very little friction upon the paper due to these guides. Furthermore, the shield 114 is of such a nature that it does not present any serious friction to the movement of the paper.

Referring now to Figures 10 and 11 there is shown a slight modification of the device where-in a second spindle 27a exactly like the spindle 27 is used to wind up the carbon strip after it is utilized. The mounting of the two spindles is the same and the description of one mounting is believed to be sufficient for the purposes of this application. Figure 4 of the drawings shows that the spindle is held between two stub shafts 147 and 148 that are journaled in the side frames 24 and 25. The shaft 147 is slidable to permit release of the spindle 27 and the shaft has a head portion 149 having a flattened portion that fits against a flattened portion 150 of a member that is fastened in each end of the spindle. The head portion on the stub shaft 148 is shaped the same way so that spindles are reversible in the machine without any difficulty. A spring 151 urges the shaft 147 into a position to hold the spindle in engagement with the shafts 147 and 148.

In the main form of the invention the spindle shafts 147 and 148 both have knurled knobs 152 and 153 thereon. However, in the modified form of the invention where the additional spindle 27a is mounted I provide the shaft 148' corresponding to the shaft 148 in said main form with a pulley 154 and I provide the shaft 155 of the spindle 27a with a smaller pulley 156. A spring belt 157 connects the pulleys so that upon rotation of the platen roller to turn the spindle 27 and thus advance the carbon strip 11, the pulley 154 is driven, and it in turn drives the other pulley in the proper direction to wind up the carbon strip on the spindle 27a. The tendency of course will be to wind the carbon too fast, but the spring belt 157 will allow slippage before the carbon strip is drawn so taut as to tear the strip. The

carbon strip as it is wound on the spindle 27a must be covered so that the master sheet 10 will not strike the surface of the carbon. I provide a shield plate 158 which is substantially semi-circular in shape and which is mounted upon a cross rod 159 that connects the side frames 24 and 25 in the modified construction.

In line with the fundamental purpose of this invention I so construct the carbon strip 11 as to make it unnecessary for the operator to handle the carbon strip in either loading or unloading the attachment. This is accomplished by providing the carbon strip with long leaders of white paper or equivalent at its opposite ends. The length of the leader should be such as to extend from the spindle 27 around the platen onto the spindle 27a far enough to secure it so that the advance of the strip would thereafter be assured without the necessity of the operator handling the carbon strip itself. Likewise in the form of the invention shown in Figure 7 the end strip which is free of carbon must be of such length as to extend from the spindle 27 around the platen roller through the channel 30 and over the bar 43 into the receptacle 28. This length of leader protects the roller in handling and shipping and protects the operator in loading and unloading the apparatus. Smearing of the sheets 10 is prevented by the shield 114. The shield is easily replaced and if at any time it becomes damaged, a new shield can be inserted without difficulty.

From the foregoing description it is believed that the nature and advantages of my invention will be apparent to those skilled in the art.

Having thus described my invention, I claim:

1. The combination with a writing machine or imprinting apparatus having a platen, of means for producing master sheets thereon, comprising means disposed behind said platen and extending forwardly and beneath the same for guiding sheet material across said platen, means for feeding a carbon strip across said platen between said sheet material and said platen, impression producing means cooperating with said platen at a fixed station, and an adjustably mounted shield disposed between said guiding means and said platen and adapted to be moved into and out of position between said strip and sheet material at said station but adapted to separate said strip and sheet material at all other points rearwardly of said station.

2. In an apparatus operating on a carbon strip, a carbon strip supply reel, a detachably mounted substantially cylindrical disposal container, means for feeding said strip from said reel to said apparatus and into said container in a substantially tangential direction, whereby said strip will become rolled up in said container without the use of a winding spool, and means adjacent said container for severing said strip.

3. The combination with a writing machine or imprinting apparatus having a roller platen, of means for producing master sheets thereon, comprising impression producing means, means for feeding a carbon strip to said impression producing means by rotation of said platen, said strip extending partially around said platen in engagement with the surface thereof, means for guiding master sheet material around a portion of said platen, and a flexible shield supported at one edge behind said platen and extending forwardly between said guiding means and said strip whereby rotation of said platen in a direction to feed the carbon strip will maintain said flexible shield in unwrinkled condition.

4. The combination with a writing machine or imprinting apparatus having a roller platen, of means for producing master sheets thereon, comprising impression producing means, means for feeding a carbon strip to said impression producing means by rotation of said platen, said strip extending partially around said platen in engagement with the surface thereof, means for guiding master sheet material around a portion of said platen, and a flexible shield interposed between said guiding means and said strip.

5. The combination with a writing machine or imprinting apparatus having a roller platen, of means for producing master sheets thereon, comprising impression producing means, means for feeding a carbon strip to said impression producing means by rotation of said platen, means for feeding master sheet material to said impression producing means operable independently of said platen, and means adapted to be interposed between said carbon strip and said master sheet material at said impression producing means.

6. The combination with a writing machine or imprinting apparatus having a platen, of means for producing master sheets thereon, comprising means for guiding sheet material across said platen, means for feeding a carbon strip across said platen between said sheet material and said platen, impression producing means cooperating with said platen, means for advancing said sheet material along said guiding means and past said impression producing means at a rate different from that at which said carbon strip is fed by said feeding means, and adjustably mounted means overlying said guiding means for holding said carbon strip out of engagement with said sheet material at certain points and operable at will to cause said strip to make a mirror impression on said sheet material by the action of said impression producing means or to render said strip ineffective to make such impression and to prevent smudging as said sheet material is advanced relative to said carbon strip.

7. The combination with a writing machine or imprinting apparatus having a roller platen, of means for producing master sheets thereon, comprising impression producing means, means for feeding a carbon strip to said impression producing means by rotation of said platen, distinct means for feeding sheet material to said impression producing means at a different rate than that at which said carbon strip is fed, and means operable at will to cause said strip to make a mirror impression on said sheet material by the action of said impression producing means or to render said strip ineffective to make such impression and to prevent smudging as said sheet material is advanced relative to said carbon strip.

8. The combination with a writing machine, of means for producing master sheets thereon, comprising means for feeding master sheet material and a carbon strip into cooperative relation with the impression producing means of said writing machine, said feeding means being adapted to move said master sheet material relative to said carbon strip during its feeding operations, and means for preventing smudging of said master sheet material by such relative movement, said smudge preventing means being adjustable at will to permit or to prevent the making of a mirror impression on said sheet material from said carbon strip by said impression producing means.

9. The combination with a writing machine, of means for producing master sheets thereon, com-

11

prising means for feeding master sheet material and a carbon strip into cooperative relation with the impression producing means of said writing machine, and means for providing engagement between said carbon strip and sheet material only in the area in which the same are in cooperative relation to said impression producing means to produce a mirror impression on said sheet material, said means being adjustable to prevent such engagement.

10. The combination with a writing machine or imprinting apparatus having a platen, of means for producing master sheets thereon, comprising means disposed behind said platen and extending forwardly and beneath the same for guiding sheet material across said platen, means for feeding a carbon strip across said platen between said sheet material and said platen comprising a feeding spindle, a receiving spindle and a driving connection between said spindles, and shiftable means overlying said guiding means for holding said carbon strip out of engagement with said sheet material.

11. The combination with a writing machine or imprinting apparatus having a platen, of means for producing master sheets thereon, comprising means disposed behind said platen and extending forwardly and beneath the same for guiding sheet material across said platen, means for feeding a carbon strip across said platen between said sheet material and said platen comprising a feeding spindle, a receiving spindle and means for rotating said spindles to maintain said strip tensioned, and shiftable means overlying said guiding means for holding said carbon strip out of engagement with said sheet material.

12. An attachment for a typewriter having a platen roll for printing reversed carbon masters, comprising a roller bearing against said platen whereby a carbon strip disposed between said roller and said platen may be advanced by rotation of said platen, means for advancing a master sheet around said platen independently of the rotation of said platen, and common control means for rotating said platen and for operating said master sheet advancing means at

differential rates of speed in order to cause relative movement of said carbon strip and of said master sheet with respect to said carbon strip, said common control means including means for adjusting the rate at which said master sheet is advanced in combination with means for rotating said platen at a constant rate of speed, irrespective of the rate of speed at which said master sheet is advanced.

13. An attachment for a typewriter having a platen roll for printing reversed carbon masters, comprising a roller engaging the surface of said platen whereby a carbon strip disposed between said roller and said platen may be advanced by rotation of said platen, means for advancing a master sheet around said platen independently of the rotation of said platen, common control means for rotating said platen and for operating said master sheet advancing means at differential rates of speed in order to cause relative movement of said carbon strip and of said master sheet with respect to said carbon strip, and a flexible shield disposed around said platen and adapted to separate said carbon strip from said master sheet in order to prevent smudging of said master sheet by the relative motion thereof with respect to said carbon strip.

CHARLES A. BERGSTEN.
